UNITED STATES PATENT OFFICE

134,397

DESIGN FOR A BUILDING

Joseph A. Chambers, Memphis, Tenn.

Application July 17, 1942, Serial No. 107,586

Term of patent 7 years

To all whom it may concern:

Be it known that Joseph A. Chambers, a citizen of the United States, residing at Memphis, in the county of Shelby and State of Tennessee, has invented a new, original, and ornamental Design for a Building, of which the following is a specification, reference being had to the accompanying drawing, forming part thereof, wherein:

Figure 1 is a front perspective view of a building showing my new design.

Figure 2 is a perspective view showing the rear of the building.

The opposite side of the building is substantially similar to that shown.

I claim:

The ornamental design for a building, as shown and described.

JOSEPH A. CHAMBERS.
